J. HOLTZMAN.

SASH LOCK,

APPLICATION FILED MAY 6, 1915.

1,221,799.

Patented Apr. 3, 1917

Inventor

John Holtzman.
By his Attorney
Benjamin Johnson.

UNITED STATES PATENT OFFICE.

JOHN HOLTZMAN, OF NEW YORK, N. Y., ASSIGNOR OF ONE-HALF TO BENJAMIN ROMAN,
OF NEW YORK, N. Y.

SASH-LOCK.

1,221,799.

Specification of Letters Patent.

Patented Apr. 3, 1917.

Application filed May 6, 1915. Serial No. 26,257.

To all whom it may concern:

Be it known that I, JOHN HOLTZMAN, a citizen of the United States, and resident of the city of New York, in the county of New York and State of New York, have invented a certain new and useful Sash-Lock, of which the following is a specification.

This invention relates to sash locks that are intended for locking window sashes in any partially opened position in the type of windows wherein an upper and a lower sash guided in ways are slideable upwardly and downwardly for opening and closing the window.

The principal object of my invention is to provide a simplified, inexpensive, strong, durable, and improved sash lock that can be economically manufactured and sold at low cost, that can be conveniently and rapidly installed by the purchaser, and that can be operated conveniently and efficiently after installation to lock the sashes, to be rendered inoperative, and to prevent unlocking thereof by a burglar or intruder reaching thereto with an implement from the exterior for the purpose of unlocking the sashes.

Another object of the invention is to provide a simple, inexpensive, and improved sash lock that will effectively lock the sashes and simultaneously operate to automatically retain the sashes against their guiding ways at all times to prevent rattling of the sashes in windy weather.

Other objects and advantages will herein-after appear.

In the accompanying drawings,—

Figure 1 is a general side elevation of the lock showing it in operative position.

Fig. 2 is a front elevation of the lock shown in Fig. 1.

Fig. 3 is a view similar to Fig. 1 but showing the lock in inoperative position.

Figs. 4 and 5 are plan views of the lock-base and the locking cam respectively.

An upper window sash 1 and a lower window sash 2 are framed within guiding ways of the window-frame, not shown, whereby they are slideable upwardly and downwardly for opening or closing the window to any greater or lesser extent. The sash lock 3 comprises a base 4 carrying a pivoted cam 5 and is fastened upon the top rail 6 of the lower sash 2 adjacent to one of the vertical sides 1^a of the upper sash-frame 1. Said base consists of a single piece

of sheet-metal which is punched out to form a bottom-plate 7, laps 8 extending therefrom, and a pair of upstanding parallel ears 9 extending from the sides of the bottom-plate. The lock is secured to the top rail 6 by means of screws 10 passing through the laps 8 threading into the rail, and when the lock is alined in properly secured position the ears 9 of base 4 are disposed perpendicularly to the plane in which the sash 1 slides. A brace-pin 11 passes through openings 12 provided in the ears 9 and is riveted in place horizontally and perpendicularly thereto. Upon the pin 11 is mounted the cam 5 which consists of a single piece of sheet-metal punched out to form a segmental cam-plate 13, having a convex serrated cam-surface 14, and wings 15 extending from the cam plate perpendicularly thereto and parallel to each other. The wings 15 are adapted to fit between the ears 9 and are provided with bearing-openings 16 which are fitted over the pin 11 in the assembling of the lock, whereby the cam 5 is hinged upon said pin and the cam plate 13 thereof is thus adapted to swing about the pin as its pivot toward and away from the sash 1 and toward and away from the plane in which said sash slides. Said cam plate has its cam-surface 14 eccentric to and increasing in distance from the pin 11 as shown, and it normally bears against the side 1^a of upper sash 1, whereby the cam is caused to bind against the upper sash upon any attempt to move this sash downwardly or the lower sash 2 upwardly. And the greater the force that is applied to open either of the sashes the firmer does the cam 5 bind against the upper sash and thereby locks both sashes securely, while at the same time the upper sash 1 may be freely moved upwardly and the lower sash 2 downwardly if it is desired to close the window. A spring 17 having one end 18 secured to the pin 11 is wound therearound and has its other end 19 extending therefrom and disposed upon the inner surface of cam-plate 13. Said spring draws the cam 5 tending to turn it about the pin 11 in a counter clockwise direction, as viewed in the drawing, and therefore tends to normally press the cam surface 14 against the sash 1, whereby a firm initial gripping of the cam surface 14 against the sash 1 is secured resulting in effective locking of the cam and the sashes. The spring 110

17 also compels the cam-plate 13 to cause the sashes 1, 2 to bear against their respective guiding ways and in this manner operates automatically to effectively prevent rattling 5 of the windows at all times.

One of the wings 15^a is made longer to extend beyond the pivot-pin 11, and a screw 20 having a knurled head 21 threads through the ear 9 adjacent said wing in a direction 10 perpendicularly thereto and in the path of the movement of said wing so that when the cam 5 is in its operative position shown in Fig. 1 the wing-edge 22 abuts against the shank of said screw and prevents swinging 15 of the cam in a direction contrary to the pressure of spring 17. The screw 20 therefore locks the cam securely in its normal operative position and thereby insures against the liability of an intruder releasing 20 or swinging of the cam-plate 13 away from the sash 1 by reaching thereto and lifting it with a hooked wire or similar contrivance from the exterior through the partially opened sash. Upon unthreading the locking-screw 20 until its extremity is alined 25 flush with the inner surface of ear 9, Fig. 4, the operator may press downwardly upon wing 15^a and therewith freely swing the cam 5 from its operative position to the inoperative position shown in Fig. 3 and back, 30 in order to set and lock the sashes in any partially opened position. Should it be desired to maintain the cam in released inoperative position, for cleaning the window-panes or for any other purpose, the wing 15^a 35 may be pressed downwardly to dispose the cam 5 to the position shown in Fig. 3, and the screw 20 may be then threaded inwardly and caused to pass through an opening 23 40 provided in said wing, by which means the cam is firmly retained and securely locked away from the sash 1. Unthreading of the locking-screw 20 to the position shown in Fig. 4 at once causes the spring 17 to restore 45 the cam 5 to its operative position in locked state against the sash 1.

In the assembling of the sash lock during its manufacture, the cam-wings 15 are inserted between the ears 9, a rivet constituting the brace-pin 11 is passed through the openings in said wings and ears and through the wound portion of spring 17 and is riveted in place to hold said parts together, and upon securing the spring-end 18 to pin 11 50 and threading the locking-screw 20 inwardly the sash lock is at once rendered 55

complete and ready for sale or installation. The installation of the lock merely requires to dispose the cam 5 so that the wing-edge 22 abuts against the screw 20, to aline the lock in proper disposition upon the sash rail 6 with its cam-face 14 bearing against the sash-side 1^a, and then the screws 10 may be threaded into the rail 6 through openings provided in the laps 8. Due to the laps 8 extending away from the remaining parts of the lock ample convenience is afforded in applying a screw driver for inserting the fastening screws therethrough when installing the sash lock. 70

It will be evident that the sash lock can be manufactured and sold at very low cost, so as to be within the purchasing reach of all users, and can be readily installed by the mere insertion of the screws 10. After installation the lock will carry out all of its functions efficiently, operate conveniently, and will never get out of order. 75

Variations may be resorted to within the scope of the invention, and portions of the improvements may be used without others. 80

Having thus described my invention, I claim:—

1. A sash lock having the combination of a base adapted to be secured to the lower window sash, a friction cam fulcrumed on said base having a convex surface eccentric to the fulcrum adapted to frictionally engage the upper sash, means to press said cam against the upper sash, and a screw threading through said base having its shank interposed to arrest movement of said cam whereby it will lock it in operative position. 85 90

2. A sash lock having the combination of a base adapted to be secured to the lower window sash, a friction cam fulcrumed on said base having a convex surface eccentric to the fulcrum adapted to frictionally engage the upper sash, means to press said cam against the upper sash, and a screw threading through said base having its shank interposed to arrest movement of said cam whereby it will lock it in operative position 95 100 and also in inoperative position.

Signed at the city of New York, in the county of New York, and State of New York, this 5th day of May, A. D. 1915.

JOHN HOLTZMAN.
